CLARENCE D. SMYTH, OF ROX, NEVADA, AND GUY M. ROBEY, OF LOS ANGELES, CALIFORNIA.

TRAFFIC SIGNAL.

Application filed July 15, 1924. Serial No. 726,139.

This invention relates to automatic signal apparatus and more especially to street and highway traffic signal systems.

One of the objects of this invention is to provide a semaphore having signal faces designated by desired words, or other effective media, which are highly efficient as signals both for day and night use, and which require no lamp illumination for day-light hours.

Signals have been proposed and tried out which involve translucent signs rendered effective by lamp light behind the signs. These are not satisfactory for daylight use because of insufficient contrast between the concealed artificial light in the signal and natural daylight. One object, therefore, of this invention is to eliminate all forms of artificial light, translucent signal media.

An object is to eliminate semaphore arms and to provide fixed sign elements and movable sign "drops" each respectively lettered (or otherwise marked) and so co-ordinated as to alternately cause change of traffic movement by automatically changing the displayed signals of the apparatus.

An important object is to provide a device which is at once simple and substantial in construction, is readily adaptable by design and arrangement to meet the various angles of highway intersections, may be either suspended from overhead or supported on pedestal or column, and is effective and reliable in its action.

An object is to provide an unitary and compact, housed signal operating mechanism, and to provide a motor-driven signal operating means adapted to be bodily removed as a power plant from the house and another, duplicate in organization, installed, all in a moment's time, so that the signal is placed out of commission but a very short time when repairs or other attention so demand. An object is to provide for accessibility to the signal mechanism without interruption of operation.

An object is to provide a signal system including the requisite "stop" and "go" signs, together with means whereby signals may all be set to give "go" signs concurrently on its several display sides, as during light traffic days and hours when control is not desired.

An object is to provide for the giving of a signal to hold all traffic for any period at

any time, when emergency demands, and to give, in such emergency, both audible and visible signals, preferably concurrently, and to set a number of "fire" signals in display and at the same time obliterate all "go" signs while the fire alarm or signal is effective.

Another object is to provide for transmitting intelligence signals by means of certain of the traffic signal apparatus.

Numerous other objects and advantages will be made manifest in the following specification of an illustrated embodiment of apparatus of the invention; it being understood that variations, modifications and adaptations may be resorted to within the spirit of the invention and within its scope as here claimed.

The invention consists of means for accomplishing the objects.

Fig. 1 is a perspective of the sign apparatus giving "fire" signal.

Fig. 2 illustrates the sign apparatus set to give signals "stop" and "go" for lines of traffic.

Fig. 3 illustrates the sign apparatus giving concurrent "go" for intersecting lines of traffic.

Fig. 4 is a diagram of the electrical controls of the apparatus.

Fig. 5 is a central, vertical section of the signal house.

Fig. 6 is an elevation of the house, one curtain being broken away.

Fig. 7 is a horizontal section of the house.

Fig. 8 is a side view of a detached power plant.

Fig. 9 is a vertical section on line 9-9 of Fig. 7, the motor shelf being omitted.

Fig. 10 is a plan of parts in Fig. 9, showing the "drop" releasing means.

Fig. 11 is a perspective of a "drop" element.

Fig. 12 is a perspective of a certain element.

Fig. 13 is a perspective of a slotted, fixed, double sign member or wall.

The signal structure.

The signal structure, of which any member may be concurrently operated in a traffic system, consists of a house, to be suitably supported, having corner posts 2 on frames

3. A perforate bottom 4 allows for sound emanation from an enclosed bell B and pro-

100

105

110

tects the interior from access upwardly by birds and insects. A hood 5 fits down tightly over the house and may be locked or secured in any manner.

- 5 On the hood is preferably provided a beacon light L to be flashed.

In the upper part of the house is a shelf 7 downwardly deflected at 8 and secured at its arm ends to fixed wall studs 9. This 10 shelf also has a central guide rod 10 extending to the bottom of the house.

Excepting on one side of the house are side walls 11 fixed to the corner posts and studs. The corner posts may be economically made of angle-iron and have their flange edges grooved from top to bottom to form channel 12. Angle bars 13 are shown as clinching the walls 11 in their angle posts.

One side wall 14 is mounted on a hinge 15 20 so as to open out and enable access into the house.

The outer edge of the swinging wall may be locked closed by a key lock 16, Fig. 7.

The side wall 11-14, which may be of 25 sheet metal, have central slots 17 to their top edges and in these lie, in the plane of the walls, filler blinds or strips 18 the lower ends of which are out-turned at 19 and connect with sliding elements 20 here called 30 "curtains" because of their functions of covering the front lower portions of their side walls, which it here may be said, have front faces designated with the word "Fire," Figs. 1 and 6.

35 The curtains 20, one for each signalling face, run at their vertical edges in channels 12 of the corner posts and they are detachably secured, as by screws 21, to the ends of cross-head arms 22 of which there is one 40 for each effective side of the house. These arms radiate from a slide 23 on guide rod 10.

Above the cross-head 22 is another sliding carrier or cross-head with arms 24 and a slide 25 running on guide rod 10. The 45 studs 9 are spaced in pairs to receive and guide all the arms of the cross-heads.

Working, above the curtains 20, in the channels 12 are elements 26 here termed "drops"; one at each signal face of the 50 house. In the form shown, each drop 26 has a goose-neck 27, from its upper edge, whose lower end 28 either rests on a lower cross-head arm 22, Fig. 9, or stands on an upper arm 24.

55 The goose-necks reach down in rear of the slot closing blinds 18.

It is desirable to lift or lower all four of the drops 26 concurrently and it is therefore necessary to provide for coupling the 60 goose-necks 27, which rest on arms 22, to the arms 24 for action therewith. Again, it is desirable to lift certain drops 26 and leave others down while the upper cross-head is up or going up. Means are provided to accomplish this. On cross-head 24

is a set of bolts 29 to be thrust into keepers or perforations 30 of goose-necks 27, Figs. 9 and 10. These bolts normally engage in their goose-necks 27 to carry them with cross-head 24 but may be tripped to release 70 two of the respective "drops" 26 on requirement from cross-head 24. One means of effecting such release includes a lever 31 connecting the bolts and operative electro-mechanically, as by a solenoid 32 mounted on 75 the cross-head 24.

Again it is desirable to lift all of the curtains 20 together with the drops to expose the "fire" signal. To that end a latch 33 is provided to lock the two cross-heads 22-24 80 together. The latch is carried by one cross-head 24 and engages the other cross-head 22, this action being controlled electro-mechanically as by an electromagnet 34.

Various suitable forms of means may be 85 devised for lifting and lowering the curtains and the drops, the cross-heads forming a simple means. As here shown the upper cross-head has a hook 35 in its slide 25 and from this extends a cable, or other connection, 36 leading over guide pulleys 37 to a crank 38, Fig. 8, on a slow speed wheel 39. This is driven by an electric (or other) motor 40 which is preferably mounted, with the driving gear, on a bed 41 which can be 90 readily passed into the house and set on shelf 7. To facilitate this convenience of assembly and removal of the power plant there is provided a cover or door 43 hinged at 44 and covering a side opening at the top 100 of the movable side wall 14. The motor and the gearing are mounted on the bed 41 and can be passed in and out as a unit when the door 43 is open. The deflected part 8 of the shelf 7 clears the motor shell when this is 105 passed in or out and so permits for compact construction and design of parts.

At each signal side, of which any number may be employed according to the angle of intersection of roadways, there is provided 110 electric (or other) light means as bulbs 45 to illuminate the front faces of the signal elements, when exposed to view. These bulbs are preferably partly covered by shielding reflectors 46 fully protecting traffic 115 drivers and others from direct rays but brightly displaying the signals without blinding the traffic by glare. The angle of incidence on the signal faces is such that there is no horizontal, blinding reflection 120 from the faces which are preferably of "flat" or dull finish; the signal media being distinguishable by contrast against the flat, plane face. The signal elements being opaque no horizontal rays of light pass 125 through and blurred or confusing signals cannot be presented.

Weather strip 48 may be employed to close the crevices along the bottom edges of the reflector backs 47 and closure 43,

A half-turn of the crank 38, by motor 40, will lift the movable signal elements so as to uncover the nether, concealed signs and a further half revolution will return the lifted signs to lower position.

The apparatus may have but one or any number of signalling faces and is here shown as for the usual right angle intersection of streets where it is desired to give duplex signals concurrently on opposite faces: Hence a pair of opposite elements 26 are designated "go" for opposed lines of traffic and another set is designated "stop." The walls 11-14 beneath the movable "go" signs are marked "stop" and the walls 11-11 beneath the movable "stop" signs are marked "go." Therefore, when the movable elements 26 are down traffic in say N. and S. directions is stopped while E. and W. traffic is signalled "go." When the signs 26 are moved an alarm is sounded by bell B and a red light signal given by the beacon L holding all traffic for a clearing period.

When the signs 26 are fully up they uncover the nether signal face and these, open N. and S. traffic and close E. and W. traffic. After a suitable traffic flow period the alarms are again given and the signs 26 lowered.

The lower portion of the fixed wall faces 11-14 under all of the curtains are marked "fire" and when all curtains are lifted the fire signals are set and all traffic stopped.

35 The control system.

At a main or central station is a main switch M and a duplex switch panel and automatic timing means for controlling the remote signal apparatuses, of which any number may be employed. One full and a part of the other of the duplex controls is shown and here described it being understood that the main switch M will be thrown from one to the other to make a change in event of necessity so as to avoid throwing the signalling apparatus out of service. The main switch M is attached at its lower end to movable contacts M' (shown vertical) to swing over from one duplex system to the other.

The central station panel has a bank of service connector groups 50 for the system of signal house apparatus and the connector groups have a master shift gang switch 51 to throw from one timer panel to the other. The drawing shows, in Fig. 4, switch blades 52^a lying open between two series of terminals, one for each of the above mentioned, duplicate, or reserve, automatic timer panels, and switch M is connected to bar 51 so that the switches 52^a can be thrown from one panel to the other as needed.

In the following description the switch-over-blades of switch 51 have been considered closed and forming continuations of the

several circuit lines, and the main switches M and S considered closed.

From the switch M runs feed line 52 to a panel switch S, thence to gang blade 52^a and thence by a connector 50 to the remote motor 40 (or motors if more houses are in circuit). Feeder 52 has a lateral 52^b, and a lateral 52^c.

Each panel includes a suitable timer A automatically operating to close the circuit of motor 40 at predetermined intervals and to the timer runs a feed line 53 having a cut-out switch T. This line has two brushes 53^a and 53^b, one of which engages a contact 54 and the other engages a contact 55; of timer A. The timer has a brush 54^a engageable with contact 54 and from it runs a line 53^c to a remote brush 53^d engageable with a breaker contact 53^e which leads by line 53^f to motor 40 thus completing a motor circuit when and only when brushes 53^a, 54^a, contact 54, and brush 53^d and contact 53^e are all concurrently in closed relation. The contact 53^e is shifted by the motor 40, when operating to change signs and is so timed in position that as the movable sign elements complete the change the circuit by line 53^c is opened and motor 40 stopped.

Contact 54 may control down stroke of the signs, and contact 55 of timer A, may control the up stroke. These contacts are designed to serve current for a period required to complete a shift of signs, and contact 53^e is local to its motor and will break its circuit at the proper moment, irrespective of the contact 54. This is to insure independence of motor action at the several intersection houses.

Contact 55 is engageable with brush 53^b and a line 55^a, to a moving contact 55^b associated with contact 53^e. From contact 55^b a line 55^c leads to motor 40 by line 53^f. If contacts 55 and 55^b are in closed relation with their brushes this will form another circuit for the motor. When the up stroke of each sign combination, in respective houses, is completed its respective contact 55^b breaks its own motor circuit.

The timer A initiates motor action of all motors in a system, and the circuit breaker of each house stops its own motor at the proper instant after lifting or lowering its sign elements.

At the main panel or central station is a bell switch B' between line 53 and line 57 to the bell B which connects with feed line 52^c. Thus a signal can be manually sent from the central station by sounding signals from the bell. The bell is also sounded automatically, with change of signs at the house, through line 57^a to circuit breaker contact 58 engageable by a brush 58 having a line 60 to line 55^c to motor 40. While either motor circuit is closed, or for a part of the period, the bell B rings.

As an additional alarm signal to hold

traffic during a change of signs, the circuit to the beacon L is closed and a strong colored light is shown. For this purpose the light is parallel circuited with the bell by lines 61-62.

To stop all traffic in emergency, as of fire, the latch 33 can be actuated by control from central to lock the lower cross-head 22 to the upper cross-head 24 so that the "fire" signs 10 will be displayed. This is effected by closing fire switch F, at central, from which leads line 63 to magnet 34, thence by line 64 to lateral 52^b, completing the circuit. When the latch 33 is set, then on the next up stroke 15 of the driving gear crank 28 the curtains are lifted and "fire" signals shown. When the latch is set, current is shunted by line 65 to the bell and the beacon and these are energized to give alarms. By opening timer 20 switch T the motor circuits will be broken and the signal mechanism rendered inoperative while the fire signal is on.

This present signalling apparatus requires no illumination of its sign faces while there 25 is enough day-light and lamps 45 are to be turned on only in darkness. This is done by a lamp switch or switches anywhere in the system. A lamp switch I is shown at central station having a line 66 to lamps 45 30 which have a line 67 to lateral 52^b.

To set the signals to indicate "go" in all directions, when desired, as after busy hours, and on Sundays and holidays, it is only necessary to disconnect those of the movable 35 signals 26 having "Go" indicia from those movable elements 26 showing "Stop" so that the latter may be pulled clear of the fixed "go" signs and leave the released drops showing "Go" down over the fixed "stop" 40 signs, as in Fig. 3. The release of the "go" drops 26 from the "stop" drops is controlled manually at any desired point in the system. A switch G is shown at central station having line 68 to the electromechanical device 32 45 controlling the bolts 29. The feed lateral 52^b connects to the device 32 making its circuit complete. To throw the bolts to again hitch up the movable drops 26, the switch G can be thrown on line 69 to reverse the magnetic device.

What is claimed is:

1. A traffic signal including a housing having fixed walls with outer traffic sign faces, a set of slidable traffic sign plates operative to cover and uncover the relative fixed sign faces; means to conceal the plates in one position in the housing, said fixed walls having also "Fire" indicia, movable curtains lying over the said indicia, and means for moving the plates alone and for moving them and the curtains together to cover the traffic signals and disclose the "Fire" indicia.

2. A traffic controlling apparatus including a support having a set of non-mov-

ing signs facing in different directions, a set of movable word signal drops means for concurrently and unidirectionally moving the drops to cover or uncover the said signs, and means for concealing the movable drops when in a position uncovering the fixed signs.

3. A traffic controlling apparatus including a housing having fixed face wall with traffic signs thereon facing different directions, and having lower indicia portions, guides at the upright corners of the housing, an upper set of movable sign bearing plates in the guides, means to move the plates and to uncover the said signs and means to then conceal them in the housing, and a second set of movable non-sign, curtain plates in the same guides, and means to shift the curtain plates after the first plates have been withdrawn, to cover the said signs and uncover the lower indicia portion of the housing.

4. A traffic controlling apparatus having non-moving signal faces showing opposed signals for crossing lines of traffic, groups of sign plates coordinate to the respective faces and having indications opposite to the said faces, means to change position of all plates for indicating reverse signals by the apparatus, and means for connecting or releasing certain of the plates so that one set only will shift; whereby a uniform signal may be made and leave the other effective.

5. A traffic signal having fixed "stop" and "go" signal faces for a traffic crossing, a set of slides with "go" media and another set of slides with "stop" media arranged to cover and uncover the said fixed faces and showing contrary signals relative thereto, connecting means for the sets of slides, automatic means for relatively shifting the said slides and fixed signal faces to alternate given signs, and manually operative control means for disconnecting one set of slides from the other and effecting a display of all of the "go" only and concurrently.

6. A traffic signal having fixed "go" and "stop" signal faces for crossing traffic lines indexed slides arranged to cover and uncover respective faces and having contrary indications relative thereto and connecting means for the slides, means for shifting the slides to effect a reverse of signs, means for disconnecting selected slides showing "Stop" from the "Go" slides for effecting a display of all of the "go" signals only at a time, and means adapted to obliterate all of the Go and Stop signals.

7. A traffic signal apparatus including a fixed traffic regulating signal, a drop sign arranged to cover said signal, means to retract the sign, a curtain, means for operating the curtain at will to replace the drop sign and cover said signal when the said sign is shifted, and including means for operatively

70

130

connecting the drop sign and the curtain to effect such replacement.

8. A signal casing, an upper set of signal drops operatively mounted in the casing, 5 means connecting the drops for coaction and including a slide, a lower set of curtain elements coordinate to the drops and a carrier therefor, means for operating the slide to raise and lower the drops independently of 10 the set of said elements, and means for connecting the slide and the carrier for concurrent action, said signal drops having go-stop signal media for intersecting traffic lines, said casing having go-stop indicia 15 contrary to the respective drops, and warning signals on the casing which are exposed when the curtains are raised, said drops being movable into a position to conceal the said media.
20. 9. A traffic signal apparatus including a housing having fixed walls with "stop" and "go" signs, upper movable sign plates for covering the signs, means to conceal the plates in one position in the housing, a 25 means for movably mounting cross-head to which the plates are operatively connected, means for actuating the cross-head, to move the plates and uncover the said signs, and means whereby predetermined plates may 30 be disconnected at will from the cross-head to cover coordinate signs only.
10. In a traffic signal, a set of cross-heads each carrying signal display means, means

for normally operating only one cross-head, and manually controlled means for connecting the cross-heads at will for concurrent action to shift the display means to ineffective position. 35

11. Signal apparatus including a guide structure, a fixed, inner signal wall, an outer 40 slideable signal element movable in the guide structure to cover the inner wall, said wall and elements having contrary traffic signal media, and the inner wall having a slot; a 45 curtain slidably mounted in the guide structure, means for raising and lowering the curtain and including a part working along the said slot, and a blind attached to the curtain and filling the slot when the curtain is in lower position, and means to raise the 50 outer wall to uncover the inner wall and the blind therein.

12. A traffic signal including a "fire" sign, a curtain therefor, fixed wall sets of plates and movable sets of members having 55 signal faces with "go" and "stop" signs, those of one set covering and being contrary to those of the other set, means for moving the movable sets of members to expose the fixed sets of plates and effect a 60 change of signals and including means for shifting the curtain to display the "Fire" sign, and means to conceal the shifted members when the "Fire" sign is disclosed.
